UNITED STATES PATENT OFFICE.

FRANK J. MARTIN, OF GREENFIELD, MASSACHUSETTS.

MARKING-MACHINE.

1,262,223.

Specification of Letters Patent.

Patented Apr. 9, 1918.

Application filed May 15, 1916. Serial No. 97,632.

To all whom it may concern:

Be it known that I, FRANK J. MARTIN, a citizen of the United States of America, residing at Greenfield, in the county of Franklin and State of Massachusetts, have invented certain new and useful Improvements in Marking-Machines, of which the following is a specification.

This invention relates to marking machines, such as are used for imprinting names, symbols, size numbers, and the like on articles of various shape.

Such machines have been used heretofore and generally comprise as essential elements a reciprocable work carrying table and a reciprocable slide, carrying a marking tool. The slide and table are arranged to move at right angles to each other; first toward one another so that work on the table is forced against the marking tool while the latter traverses the work, and then away from one another to permit marked work to be removed and unmarked work to be placed on the table. Machines of this class have heretofore been mechanically operated by a rather elaborate arrangement of cams, gears, levers, and links, and are, on account of such construction, expensive to manufacture. More particularly, they are difficult to adjust to secure the various ranges of travel of the slide and table and the various pressures of the table on the work, which are necessary to meet the varying conditions of different classes of work. A further objection to the mechanical operation lies in its unyielding actuation of the slide and work carrying table. For example, assuming that the latter is adjusted for a given class of work, it will travel the correct distance for perfect pieces in that class, but, if some pieces are slightly oversize or undersize, the travel of the table will be the same as before with the possible result of breakage in the first case due to the excessive pressure or in the second case of insufficient marking due to the insufficient pressure. These disadvantages are avoided by the machine which is the subject matter of this invention.

An object of this invention is to provide in a marking machine, involving a reciprocable tool carrying slide and a work carrying table, reciprocable at right angles to the slide, hydraulic means to actuate said

slide and table which is particularly characterized by a uniform pressure of the work against the tool irrespective of irregularities in the former.

Another object of the invention is to provide in a marking machine, a hydraulically actuated marking slide and a similarly operated work carrying table together with improved means to vary the pressure of the table on the work and the speed of slide across the latter.

Another object of the invention is to provide in a marking machine a hydraulically actuated marking slide and means to vary the stroke of the slide without moving the latter or disturbing its operating devices, the arrangement of said means being characterized by quick and convenient adjustment of the slide for various travels and particularly by the possibility of making a given travel occur at various positions relatively to the table.

Other objects and advantages will appear in the detailed description to follow and in the appended claims.

For the purpose of illustrating one manner in which the invention may be practised, a single preferred embodiment thereof is illustrated in the accompanying drawings, in which,

Figure 1 is a front elevational view of the complete machine showing the general arrangement of parts with certain members shown in conventional form only;

Fig. 2 is a sectional elevation taken on the line 2—2 of Fig. 1 and looking in the direction of the arrows;

Fig. 3 is a sectional plan view of a part of the marking slide and is taken on the line 3—3 of Fig. 1 looking in the direction of the arrows;

Fig. 4 is a rear elevational view of the valve mechanism and controlling devices therefor;

Fig. 5 is an end elevational view of Fig. 4;

Fig. 6 is an elevational view showing in diagrammatical form a part of the reversing mechanism for the valve;

Figs. 7 and 8 are sectional views taken on the lines 7—7 and 8—8, respectively, of Fig. 5 and looking in the direction of the arrows;

Fig. 9 is a sectional view taken on the

75

90

105

line 9—9 of Fig. 4 and looking in the direction of the arrows; and

Fig. 10 is a plan view, partly in section, of a relief valve for controlling the pressure on the work carrying table.

Referring to these drawings in detail and particularly to Figs. 1 and 2, the frame of the machine comprises a hollow pedestal A, and a head B supported in spaced relation 10 from the pedestal by side members C. The several members A, B, and C are preferably integral parts of a single casting. Slidably mounted on the front face of pedestal A is a table 1 which is adapted to support the work 15 to be marked. In line with table 1 and disposed near the base of the machine is a cylinder 2 having a piston 3 therein which is connected by a rod 4 with the table 1. The upper end of rod 4 is threaded into table 1 20 and nuts 5 on the rod below the table provide means for varying the height of table 1 within limits as desired.

The head B is recessed to receive a slide 6 which is held thereto by suitable gibbs 7, as 25 shown in Figs. 1 and 2. Slide 6 carries a marking tool which may be of any of the well known forms, such as the roll die 8, indicated conventionally in Fig. 1. The tool 8 is adapted to be moved horizontally across 30 the work to be marked which is supported upon and forced into contact with tool 8 by the vertically movable table 1. The slide 6 is of square cross sectional shape, as shown in Fig. 2, and flat plates 9 are secured to the 35 vertical sides thereof which plates extend above slide 6 and support therebetween a plurality of rolls 10 to engage the head B. Fitted within one end of slide 6, as best shown in Fig. 3, is a sleeve 11 which is closed 40 at the outer end by a cap 12. A piston 13 within sleeve 11 is stationarily held by pipes 14 and 15 which connect the piston with a bracket D secured to head B. Cap 12 has a suitable stuffing box therein through which 45 pipes 14 and 15 pass so that sleeve 11 and thus slide 6 can move relatively to piston 13 and thus the frame of the machine. The inner pipe 15 opens at one end into sleeve 11 on the left side of piston 13 while the outer 50 pipe 14 is closed at one end by piston 13 and has several holes 16 therein which communicate with sleeve 11 to the right of the piston. The other ends of pipes 14 and 15 communicate with cored passages 17 and 18 55 which pass downwardly through bracket D and connect with pipes 20 and 19, respectively.

Supported within pedestal A is a valve 21 which is indicated in Fig. 1 only in a general way sufficient to disclose its relation 60 with the other parts of the machine. Its construction is, however, fully shown in Figs. 4, 5, 7, 8, and 9 to which reference is now made. The valve 21 has four tapped 65 openings arranged at right angles to one an-

other which are adapted to receive pipe connections as will appear. Rotatable in a closed central interior chamber 22 of the valve is a plate 23 having an integral rod extension 24 which passes out through a 70 stuffing box formed in the cover plate 25 and is adapted to be actuated by means to be described. Plate 23 has a single slot 26 therein which may register with either of two slots 27 and 28 formed in the base of the valve 75 or it may lie between said slots in neutral position, as shown in Fig. 7. Diametrically opposite slot 26, a recess 29 is formed in plate 23 facing the base of the valve. This recess may connect either of ports 30 and 31 80 with a port 32, all formed in the base of the valve, or it may simply overlie port 32 and close off ports 30 and 31 therefrom. Ports 27 and 30 are connected together and to pipe 19, heretofore mentioned, by a cored passage 85 33. Ports 28 and 31 are similarly connected by a passage 34 to pipe 20 heretofore mentioned. The port 32 is connected, as shown in Fig. 9, to an exhaust pipe 35 and a supply pipe 36 enters the valve 21 diametrically opposite from pipe 35 and leads to chamber 22 above the plate 23, as clearly shown in Fig. 9. It will be obvious that, when plate 23 is swung counterclockwise from its neutral position shown, liquid supplied to chamber 22 90 will pass through the registering ports 26 and 27 and out through pipe 19 since no other exit is provided as plate 23 closes off port 30. At the same time, ports 31 and 32 will be connected by the recess 29 so that liquid in pipe 20 may pass to exhaust pipe 35. When plate 23 is moved in a clockwise direction until ports 26 and 28 register, liquid is supplied to pipe 20 and exhausted 95 from pipe 19 in an analogous manner.

Referring to Figs. 1 and 2, a supply tank 37 is located within pedestal A near the base thereof to receive oil or other suitable fluid for actuating the slide 6 and table 1. Above tank 37 and connected therewith by a pipe 110 38 is a gear pump 39 which is adapted to be driven from a suitable source of power by a belt 40. Interposed in pipe 38 is a check valve 41 which permits upward flow through the pipe only, and at the base of the pipe an intake strainer 42. These parts, each well known, have been represented in conventional form. Pump 39 draws oil from tank 37 and forces it through pipe 36 to the valve 21 and check valve 41 prevents the oil drawn 115 into pipe 38 from passing back again to tank 37. The exhaust pipe 35 leads to the latter, as shown in Figs. 1 and 2, so that the oil used in the cylinders is redelivered to the tank to be used over again. Interposed in 120 pipe 19 is an ordinary globe valve 42', whereby the flow of oil through the pipe may be varied as desired for a reason later to appear. Pipe 36 also has a suitable gage 43 connected thereto, whereby the pressure in 125 130

the system may be indicated in the usual manner. A by-pass pipe 44 connected at one end with pipe 36 by a relief valve 45 is connected at its other end to the inlet of pump 39. This relief valve may be of any of the usual commercial types and one suitable form is shown in Fig. 10 for illustrative purposes. A spring pressed valve 46 normally closes off the connection between pipes 36 and 44, but, as soon as the pressure in the former becomes greater than the force exerted by the spring, valve 46 opens and permits the fluid to pass into pipe 44 and thus to the inlet of pump 39. The pressure on the latter is thereby eased up by the circulation around the by-pass pipe 44 in an obvious manner. The tension of the valve spring may be regulated by the hand wheel shown in Fig. 10 in an obvious manner, and this hand wheel extends without pedestal A, as shown in Figs. 1 and 10 for convenient operation. The pipes 19 and 20 lead to the sleeve 11 on opposite sides of piston 13, as already described, and pipes 57 and 58, respectively, lead from these pipes to cylinder 2 on opposite sides of piston 3, as shown in Figs. 1 and 2. The pressure regulating means is particularly important because by it the pressure between the tool and work is maintained at the desired constant.

The means for operating the valve 21 will now be described. Fixed on operating rod 24 of the valve is a lever 47 (Figs. 4 and 5) which is movable between spaced adjustable stops 48. A latch 49 pivoted at 50 to the valve casing normally holds the lever 47 from upward movement. Latch 49 is connected by a link 51 (Fig. 2) to a lever 52 on a shaft 53 which extends entirely across pedestal A, as indicated in Fig. 1. A foot lever 54 (indicated by dotted lines in Fig. 2 since it lies to the right of line 2-2 in Fig. 1) is fixed on shaft 53 and has a portion extending without the pedestal for convenient operation. A pressure on lever 54 will swing lever 52 in a counterclockwise direction and move latch 49 to release arm 47. Latch 49 moves back into arm engaging position when foot lever 54 is released by reason of a spring 55 (Fig. 2) which connects the lever 52 to a suitable fixed part, as indicated in Fig. 2.

The means for moving arm 47 will next be described with particular reference to Figs. 55 1, 2, and 6. Adjustably held in a T-slot 59 in slide 6 are spaced stops 60 and 61 and mounted in head B below slide 6 is a shaft 62 having a lever 63 fixed thereon, a portion of which lies between and in the path of stops 60 and 61, as shown in Fig. 1. Fixed on shaft 62 is an arm 64 which is connected by a link 65 to arm 47, as indicated in Fig. 4. Much of the detail in Fig. 1, however, has been omitted to avoid confusion of lines 60 owing to the small scale to which this figure

is drawn. For example, arm 47 is merely indicated, link 51 is purposely shown as broken off, and the latch 49 is entirely omitted. The particular detail is, however, fully shown in Figs. 4 to 6, inclusive, which, 70 taken with the indications given in Fig. 1, will enable a full understanding of the invention to be obtained. Fixed to shaft 62 beyond arm 64 is a cam 66 and in engagement therewith is a spring pressed roll 75 mounted in a casing 67 secured to head B. To effectively show lever 62, arm 64, and cam 66 in their correct relative positions, a diagrammatical showing of these parts has been made in Fig. 6 to which reference is now 80 made. It will be seen from this figure, that cam 66 is provided with a point which normally bears on a spring pressed roll 68 slightly above the line of centers connecting the roll and shaft 62. 85

The operation of the machine will now be described. Assuming that the stops 60 and 61 have been set to obtain the desired travel of tool 8 and that nuts 5 have been moved to raise table 1 to its desired height (the 90 stroke of the table being constant), work to be marked is placed on the table, and the operator depresses foot lever 54 which releases latch 49. Arm 47, thus released, is drawn upwardly by link 65 and lever 64, and the 95 latter is moved by the action of spring pressed roll 68 against the under side of cam 66. The latter having merely a point contact with the roll is in unstable equilibrium and has a tendency to move upwardly since 100 its contact with the roll is purposely arranged a trifle above center, as stated. Lever 63 is incidentally thrown slightly to the right, as indicated in dotted lines in Fig. 6. The actuation of arm 47 is in a 105 counterclockwise direction, as viewed in Figs. 7 and 8, so that oil is admitted to pipe 19 and exhausted from pipe 20. Accordingly oil is forced into sleeve 11 to the left of piston 13 and into cylinder 2 below piston 110 3 so that the slide 6 travels to the left and table 1 with the work moves upwardly. The work is thus forced against tool 8 as the latter is moved thereacross, and the desired marking of the work is obtained in 115 the usual manner. As slide 6 continues on its movement to the left as viewed in Fig. 1, stop 61 engages lever 63 and swings it to the left which forces the point of cam 66 below roll 68 and rocks arm 47 of the valve 120 in a clockwise direction, as viewed in Figs. 4, 7, and 8. The supply to pipes 19 and 57 is thus first closed off and shortly after these pipes are connected to exhaust pipe 35. Meanwhile connection has been established 125 between supply pipe 36 and pipe 20 so that oil is forced into the upper part of cylinder 2 to lower piston 3 therein and into sleeve 11 to the right of piston 13 to move slide 6 to the right. As slide 6 moves to the right, 130

stop 60 engages lever 63 and swings it in a clockwise direction until it lies in the vertical position, as shown in Fig. 1. Further movement of the lever is prevented since 5 arm 47 which is moved therewith comes up against the under surface of latch 49. Thus the parts are left in neutral position, as shown, and the machine comes to rest. If other than one cycle of operation, as 10 described, is desired, it may be obtained by holding lever 54 down so that latch 49 cannot engage arm 47, as the latter passes from its lower to its upper position.

The valve 42' permits regulation of the 15 speed of slide 6 by controlling the quantity of oil which passes therethrough. As the slide travels to the left, the oil forced from sleeve 11 through pipe 20 is throttled and, as the slide 6 travels to the right, the supply to sleeve 11 is throttled, whereby the 20 speed of the slide may be regulated as desired. The relief valve 45 is used to vary the pressure on table 1 by varying the tension of the valve spring so that the pressure 25 will not exceed a given and predetermined amount. The travel of the slide may be varied in an obvious manner by moving stops 60 and 61, and, if desired, the travel 30 of the slide may be made to occur unsymmetrically with the center line of table 1 to adapt itself to the particular class of work in hand. The slide heretofore used has generally been reciprocated by a crank of adjustable throw and a connecting rod. Obviously, with this arrangement, the travel of 35 the slide may be varied but not in as convenient manner as with the structure disclosed. However, the travel needs be equal on either side of the center line of the table 40 unless the latter or the crank shaft is moved the one relatively to the other. The crank and connecting rod method of operation, moreover, is by no means smooth in operation nor is its speed uniform as is obtained 45 by the structure herein described.

The invention has been described in a preferred form for the purposes of illustration, but the invention is defined in its proper scope by the appended claims rather than 50 by the foregoing description.

What I claim is—

1. A marking machine, comprising, a reciprocable tool carrying slide, a reciprocable work supporting table, said slide and table 55 arranged to move at right angles to one another, hydraulic means to simultaneously actuate said slide and table and means to maintain the pressure of the table on the work constant, all constructed and arranged 60 so that the work to be marked is brought against said tool with a constant pressure regardless of size variations in the work.

2. A marking machine, comprising, a reciprocable tool carrying slide, a reciprocable 65 table adapted to support work to be marked,

said slide and table arranged to move in rectangular relation, means to simultaneously move said slide and table to bring the work on the latter into engagement with the tool on the former, and means to maintain the pressure of the table on the work constant, including means to vary said pressure, all constructed and arranged so that the work is forced against the tool with a uniform pressure irrespective of irregularities in the work. 75

3. A marking machine, comprising, a reciprocable tool carrying slide, a reciprocable table arranged to move in rectangular relation with said slide and adapted to support work to be marked, hydraulic means to simultaneously actuate said slide and table to force the work against the tool as the latter moves across the former, a valve associated with said means, and means controlled by the travel of said slide to actuate said valve and reverse the motion of the slide and table. 80

4. A marking machine, comprising, a reciprocable tool carrying slide, a reciprocable work carrying table arranged to move in rectangular relation to the slide, hydraulic means to simultaneously actuate the slide and table to force the work against the tool as the latter travels across the former, 90 a valve associated with said means, and means controlled by the travel of the slide to actuate the valve to reverse the motion of the slide and table, said last-named means being adjustable to vary the travel of the slide and constructed and arranged so that the travel may be varied without disturbing its operating means and so that uniform travels of the slide may be made to occur at 95 various parts of the table. 100

5. A marking machine, comprising, a reciprocable marking slide, a reciprocable work supporting table arranged to travel at right angles to the slide, hydraulic means to simultaneously move the slide and table and 110 a controlling device adapted for manual operation and arranged to permit one complete cycle of operation of said slide and table, whereby the work may be forced against the slide, as the latter moves across the former in one direction and the work is withdrawn from the slide as it moves across the work in the other direction. 115

6. A marking machine, comprising, a frame, a tool carrying slide reciprocable in 120 the frame, a cylinder formed therein, a piston in said cylinder and stationarily held by the frame, a reciprocable work carrying table arranged to move at right angles to the slide, a second cylinder, a piston therein 125 adjustably connected to said table, a valve adapted to admit fluid under pressure simultaneously to said cylinders to move the slide and table toward one another, means controlled by the travel of the slide to actuate 130

said valve to reverse the motion of the slide and table and means controlled by the travel of said slide to actuate said valve to stop the slide and table.

- 5 7. A marking machine, comprising, a frame, a table supported for vertical reciprocating movements thereby, a marking slide supported above the table for horizontal reciprocatory movements, a cylinder 10 formed in said slide, a piston in the cylinder and stationarily held by said frame, a second cylinder, a piston therefor connected to said table, a valve adapted when moved in one direction to supply fluid under pressure to 15 said cylinders to move the slide and table toward one another and, when moved in the
- other direction, to move the slide and table away from one another, said valve adapted to be moved to an intermediate position to cut off the supply to said cylinders, releasable mechanism normally holding said valve in its intermediate position including a device to move the valve to its first-named position when said mechanism is released, means controlled by the movement of the 25 slide in one direction to move the valve to the second named position, and means controlled by the movement of the slide in the other direction to move the valve into its intermediate position, whereby it may 30 be held by said mechanism.

FRANK J. MARTIN.
